(57) **CLAIM**

The new design for multi-configurable footwear, as shown and described.

DESCRIPTION

FIG. 1 is a side orthogonal view of the new design of multi-configurable footwear showing a sole base, strap attachment loops attached to the upper surface of the sole base, and a changeable ornamental strap looped through the strap attachment loops.

FIG. 2 is a top orthogonal view thereof; and,

FIG. 3 is a top perspective view thereof.

The phantom lines in the drawings represent unclaimed subject matter.
